UNITED STATES PATENT OFFICE.

WILLIAM S. MACLEWEE, OF YARDLEY, PENNSYLVANIA, ASSIGNOR TO CARRIE HOWELL
MACLEWEE, OF YARDLEY, PENNSYLVANIA.

LAMP-SOCKET.

1,285,293.

Specification of Letters Patent. Patented Nov. 19, 1918.

Application filed February 12, 1916. Serial No. 77,850.

To all whom it may concern:

Be it known that I, WILLIAM S. MACLEWEE, a citizen of the United States, residing at Yardley, in the county of Bucks and

5 State of Pennsylvania, have invented certain new and useful Improvements in Lamp-Sockets, of which the following is a specification.

10 My invention relates to improvements in an electric lamp socket. The object of my invention is to construct a lamp socket having novel means for locking the two parts of the metal shell together.

15 In the accompanying drawings; Figure 1 is a view in elevation of my improved lamp socket; Fig. 2 is an elevation of the two parts of the casing detached; Fig. 3 is a horizontal section on line 3—3, Fig. 1; and Fig. 4 is a vertical section, drawn approximately on 20 line 4—4, Fig. 3.

The metal shell of the lamp socket consists of the body portion 1 and the cap 2. The body portion 1 is provided with a projecting lug 3 and the cap 2 is provided with a slot 4, and a slot 5 formed at right-angles to the slot 4. When the cap 2 is placed upon the body portion 1, the lug 3 enters the slot 4 in the cap, the latter is turned so that the lug 3 will enter the slot 5 in the cap, which 25 brings the metal tongue 6 below the lug 3, which will prevent the cap from being pulled off the body portion. Upon the body portion 1 is mounted a locking device for preventing the cap from turning upon the body portion.

30 35 The locking device consists of a stud 8 slidably mounted in a slot 9 formed in the body portion. The stud 8 is provided with two heads, the inner one of which impinges against the fiber insulating lining 10, which

holds the stud 8 in either the locked position 40 as shown in Figs. 1 and 4, or in the unlocked position, as shown in Fig. 2.

Having thus described my invention I claim and desire to secure by Letters Patent:

1. In a lamp socket the combination of a 45 metal shell consisting of two parts, a lug formed upon one of said parts, a projection upon the other one of said parts adapted to engage the lug by turning the said parts and a sliding member upon the part carrying 50 the lug adapted to engage the other one of the parts and prevent the parts from turning.

2. In a lamp socket the combination of a metal shell consisting of two parts, a lug 55 formed upon one of said parts, a right angle slot formed in the opposite one of said parts to receive said lug, and a sliding stud upon the part carrying the lug adapted to be moved into engagement with the part in 60 which the slot is formed to prevent the latter from turning.

3. In a lamp socket the combination of a metal shell consisting of a body portion and a cap, means for securing said parts together 65 by turning the cap upon the body portion, a stud slidably mounted in a slot formed in the body portion adapted to engage the cap and prevent it from turning upon the body portion when in the locked position, and a lining within the body portion adapted to press against the stud and hold it in position.

In testimony whereof I have affixed my signature in the presence of two witnesses.

WILLIAM S. MACLEWEE
